ATTORNEY

UNITED STATES PATENT OFFICE.

ARTHUR PAUL HORN, OF CINCINNATI, OHIO.

LIFEBOAT.

1,371,896.

Specification of Letters Patent. Patented Mar. 15, 1921.

Application filed October 12, 1920. Serial No. 416,356.

To all whom it may concern:

Be it known that I, ARTHUR P. HORN, a citizen of the United States, residing at Cincinnati, in the county of Hamilton and 5 State of Ohio, have invented new and useful Improvements in Lifeboats, of which the following is a specification.

This invention relates to a novel construction of life boats, the principal object of the 10 invention being to provide means for propelling the boat by manually operated means which are arranged to drive the propeller of the boat.

Another object of the invention is to provide 15 means for rotating the propeller at different speeds.

A further object of the invention is to provide a number of hand levers which are pivoted to the boat and are adapted to be 20 worked back and forth, with means for converting this movement of the levers to a rotary movement of the propeller shaft.

This invention also consists in certain other features of construction and in the 25 combination and arrangement of the several parts, to be hereinafter fully described, illustrated in the accompanying drawings and specifically pointed out in the appended claim.

30 In describing my invention in detail, reference will be had to the accompanying drawings wherein like characters denote like or corresponding parts throughout the several views, and in which:—

35 Figure 1 is a longitudinal section of a boat constructed in accordance with my invention.

Fig. 2 is a plan view.

Fig. 3 is a cross section on line 3—3 of 40 Fig. 1.

Fig. 4 is a cross section on line 4—4 of Fig. 1.

Fig. 5 is a detail plan view of the reciprocating member.

45 Fig. 6 is an enlarged view of the gearing.

In these views 1 indicates the boat in which is journaled the propeller shaft 2 which carries the propeller 3. The inner end of this propeller shaft is of square 50 shape in cross section, as shown at 4, and a number of beveled gears 5, preferably three, are slidably mounted on this square portion. These gears are provided with square holes for receiving the shaft. Each gear is provided with a grooved collar 5' in the groove 5'' of which engages the forked end of a

hand lever 6 which is pivotally connected with a stationary part. By rocking this hand lever each beveled gear can be moved into active or inactive position on the propeller shaft. A shaft 7 is arranged cross-wise of the boat and this shaft carries a large gear 8 which is provided with three rows of beveled teeth which are adapted to be engaged by the beveled gears 5 on the propeller shaft. The rows of teeth are spaced apart so as to permit the beveled gears to be moved into and out of engagement with the teeth. As will be understood, one of the beveled gears is adapted 70 to be moved into and out of engagement with the outer row of teeth, the next gear with the middle row of teeth and the third gear with the inner row so that the propeller shaft can be driven at three different 75 speeds or it can be entirely disconnected from the large gear wheel.

A reciprocating member 9 is movably supported in the uprights 10. This member is formed of two bars 9' which are bolted 80 together in spaced relation and this member is pivotally connected at one end to an arm 11 which has its other end pivotally connected with the wheel 8 by the pin 12 so that the reciprocating movement of the member 85 9 will act to rotate the wheel 8. Boxings 13 are pivotally mounted between the bars 9' of the member 9 and the actuating levers 14, which are pivoted at the lower ends to the bottom of the boat, pass through said boxings. The upper ends of the actuating levers are provided with the handles 15, so that the said levers may be rocked back and forth by hand. This movement of the levers acting on the member 9 through the boxings 13 will reciprocate said member and the reciprocation of this member will rotate the wheel 8 so that by moving the desired gear 5' in engagement with its row of teeth on the wheel 8 the propeller shaft will be 90 95 100 rotated at the desired speed.

While I have shown means for driving the propeller shaft at three speeds with two actuating levers, it will of course be understood that any desired number of gears and 105 actuating levers may be used.

It is thought from the foregoing description that the advantages and novel features of my invention will be readily apparent.

I desire it to be understood that I may 110 make changes in the construction and in the combination and arrangement of the several

parts, provided that such changes fall within the scope of the appended claim.

What I claim is:—

In combination with a boat and its propeller shaft, a second shaft arranged transversely in the boat, gears connecting the shafts together, uprights in the boat, a reciprocating frame supported by said uprights, boxings located in said frame, actu-

ating levers passing through said boxings and having their lower ends pivoted to the bottom of the boat, handles on the upper ends of said levers and means for connecting one end of said frame with the gear on the transversely arranged shaft. 15

In testimony whereof I affix my signature.

ARTHUR PAUL HORN.
